Primary Examiner — Janice Hallmark*Assistant Examiner* — Harold E Blackwell, II(74) *Attorney, Agent, or Firm* — Dinsmore & Shohl, LLP(57) **CLAIM**

The ornamental design for an equipment mounting plate, as shown and described.

DESCRIPTION

FIG. 1 is a top perspective view of an equipment mounting plate according to the present design;

FIG. 2 is a top side view of the equipment mounting plate of FIG. 1;

FIG. 3 is a bottom side view of the equipment mounting plate of FIG. 1;

FIG. 4 is a side view of the equipment mounting plate of FIG. 1 and the opposite side being the same; and,

FIG. 5 is a sectional view taken in the direction of line 5-5 of FIG. 1.

The long dash-short dash broken lines in the figures represent the bounds of the claimed design. The dash-dash broken lines in the figures illustrate portions of the equipment mounting plate which form no part of the claimed design.
